UNITED STATES PATENT OFFICE

LEIGH G. NELSON, OF CHICAGO, ILLINOIS

TRANSPARENT DISPLAY COVER

Application filed May 10, 1928. Serial No. 276,520.

This invention relates to display covers for containers for food stuff, as, for instance, evaporated fruit, candies, etc., and aims to provide a practical and efficient cover which 5 may be readily and conveniently placed upon a container permitting ready access to the same and a view of the contents thereof, at the same time protecting the contents.

The covers of the above type which have 10 been used heretofore, have usually been of glass, have been comparatively expensive to manufacture and have not been constructed to withstand rough usage.

In order to overcome these difficulties and 15 to provide a more efficient cover of the above type, I provide a cover which is constructed of relatively thin flexible material, such as celluloid, for clearness and lightness without fragility.

20 The cover may be of relatively thin material and still afford suitable rigidity, because in connection therewith I provide a relatively rigid lightweight frame preferably of relatively thin metallic material, such as aluminum or steel. The construction of this frame 25 for marginally holding the thin flexible sheet and for positioning and holding the cover upon a container, is one of the features of the present invention. When it is deemed desirable, the frame is formed of a plurality of 30 sections, and the manner of joining these sections is another feature of the present invention. Another feature resides in the manner of securing a thin flexible sheet marginally in the frame and against being pulled 35 or drawn out of the frame along its margin by pressure upon the flexible sheet within the area bounded by the frame. Another object is to permit relative contraction and expansion 40 between the frame and the margin of the thin flexible sheet without buckling or tearing the thin flexible sheet.

45 Other advantages and features of my invention will be apparent from the specification and claims when taken in conjunction with the accompanying drawings, wherein:—

Fig. 1 represents a plan view of a cover embodying this invention;

50 Fig. 2 is a perspective view of a corner of said cover;

Fig. 3 is a plan view of the corner of the frame viewed from the under side thereof;

Fig. 4 is a vertical longitudinal section of one side of said corner;

Fig. 5 is a vertical longitudinal section of 55 the other side of said corner; and

Fig. 6 is a perspective of one of the frame members showing the construction of the respective ends thereof.

Referring to the drawings more particularly, numeral 1 represents the frame members which are arranged in the manner shown to make a frame adapted to enclose therein thin flexible material 2, such as celluloid. Numeral 9 indicates the side wall of the container upon which the cover herein referred to is placed.

In construction, the frame members are 60 preferably bent from flat strips of thin, light durable material, such as aluminum or steel; these members have at the one end a tongue 3 projecting over the approximate upper one-third of the flat strips and at the other end a tongue 4 projecting over the approximate 65 central one-third of the flat strips and a tongue 5 projecting over the approximate lower one-third of said flat strips. Each tongue bears a hole or holes 8 adapted to receive rivets 6 or 7. The members are passed through a punch press or other similar machine and the approximate upper one-third of the strip is bent forward toward and nearly upon the approximate central one-third of the strip to form a groove, and the approximate lower one-third is bent backward to 70 form a right angle with said approximate central one-third of said strip.

The transparent material is then inserted 75 into the said groove of one member formed by the bending of the uppermost part of the strip nearly upon the central part, the edge of said material being placed as far into the groove as possible and the corner of said material permitted to extend to the edge of the projecting tongue or tongues. The opposite 80 end of another frame member is then placed at an angle upon or under, whichever the case may be, the projecting tongue of the member containing the transparent material and the material placed within the groove of the 85

second member. The corner formed by the placing of the members in the manner described is then placed into a machine designed to rivet or otherwise secure the two members and the corner of the transparent material together. The other members are then consecutively placed and riveted, or otherwise secured, to the members containing the transparent material in the manner described so as to form a complete frame, which may be either square, rectangular, or any other shape, depending upon the design of the members used. The tongue 5 is then bent over upon the adjacent side of the adjacent frame member and then riveted with rivet 7, or secured in another convenient manner.

It is to be noted that the transparent material enclosed within the frame may be either held securely by stamping tightly the 20 sides of the enclosing groove as well as by rivet 6, or by bending the sides of said groove together to such an extent which, while loosely holding the material, will permit ready expansion and contraction without 25 straining or breaking said material.

Another modification of this construction consists in making the holes in the corners of the transparent material through which the rivets are placed larger in size than the 30 rivets or other securing means and securing the corners tightly enough to securely hold the material, allowing enough space between the riveted member so as to permit movement of the material held thereby in the event of 35 contraction or expansion due to the elements. I consider this feature of great importance from a practical standpoint, as the rate of expansion and contraction of celluloid under temperature changes is different from 40 that of aluminum or other metal, and therefore it is desirable to allow for this difference, as otherwise the celluloid would buckle and eventually break and tear, due to uneven expansion and contraction.

45 While I have illustrated and described the preferred form of the device, changes can be resorted to without departing from the field and scope of the invention, and I intend to include in this application all such 50 variations as fall within the scope of the appended claims.

I am aware that many changes may be made without departing from the principles of this invention, and I do not wish to be 55 limited to the details shown or described.

I claim:—

1. A display cover comprising a transparent sheet, a plurality of relatively thin metallic frame members folded over the margin of 60 the sheet, one frame member having an end extension on one side of the fold overlapping an end extension on the opposite side of the fold of the adjacent frame member, and means passing through said overlapping extension and through the margin of the trans-

parent sheet for securing said frame members together and the margin of the sheet therein.

2. A display cover comprising a thin flexible transparent sheet, a frame member folded over the margin of said sheet, a second frame member folded over the margin of the sheet, overlapping extensions on said frame member, and means passing through said extensions and through the margin of the sheet 75 for securing said sheet to said frame members and said frame members together.

3. A display cover comprising a thin flexible transparent sheet, frame members adapted to receive the marginal edges of said sheet, and means securing the ends of the frame members together, said means engaging the adjacent marginal edge of the sheet to hold it therebetween.

4. A display cover comprising a thin flexible transparent sheet, frame members adapted to receive the edges of said flexible sheet, and having flanges adapted to fit within a container, and means for securing the ends of said frame members together and engaging the margins of the sheet to hold it therebetween.

5. A display cover comprising a thin, flexible, transparent sheet, a frame surrounding said sheet and overlapping the margins thereof, the overlapping margin of the sheet having openings therethrough, means passing through said openings and secured in said frame for holding the margin of the sheet in the frame, said openings being enlarged to permit relative expansion and contraction of the margin of the sheet without tearing or buckling same.

In witness whereof, I hereunto subscribe my name this 2nd day of May, 1928.

LEIGH G. NELSON.
